(57) CLAIM

The ornamental design for an asymmetrical one shoulder seamless brassiere, as described and shown.

DESCRIPTION

FIG. 1 is a front perspective view of an asymmetrical one shoulder seamless brassiere;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a front perspective view thereof, shown in an alternate configuration.

The broken lines depicting the human shown in the drawings are for environmental structure only and form no part of the claimed design.
